CLAIM

The ornamental design for a camera equipped network door station, as shown and described.

DESCRIPTION

FIG. 1 is a front, right, bottom perspective view of a camera equipped network door station showing our new design; FIG. 2 is a front elevation view thereof; FIG. 3 is a right side elevation view thereof; FIG. 4 is a left side elevation view thereof; FIG. 5 is a bottom plan view thereof; FIG. 6 is a top plan view thereof; and, FIG. 7 is a rear elevation view thereof.

The broken lines illustrate portions of the camera equipped network door station that form no part of the claimed design.
